DRY CELL CHARGING APPARATUS CASE

Hajime Ota, Tokyo, Japan, assignor to Fedtro, Inc.,
Long Island, N.Y., a corporation of New York

Filed Dec. 10, 1965, Ser. No. 137

Term of patent 14 years

(Cl. D26—15)

FIG.1

FIG.2

FIG.3

FIG.4

FIG. 5

FIG. 6

FIG. 7

FIG. 1 is a front elevational view of a dry cell charging apparatus case or similar article, showing my new design;

FIG. 2 is a rear elevational view;

FIG. 3 is a top plan view;

FIG. 4 is a bottom plan view;

FIG. 5 is a left side elevational view;

FIG. 6 is a right side elevational view; and

FIG. 7 is a left side, top and front perspective view thereof.

I claim:

The ornamental design for a dry cell charging apparatus case, substantially as shown.
